(57) **CLAIM**

The ornamental design for an ammunition cartridge nose having an angled shoulder, as shown and described.

DESCRIPTION

FIG. 1 is an isometric view of an ammunition cartridge nose having an angled shoulder showing my new design of the nose portion of an ammunition cartridge.

FIG. 2 is a top view of my new design of the nose portion of an ammunition cartridge.

FIG. 3 is a cross sectional view along 3-3 of FIG. 2 showing my new design of the nose portion of an ammunition cartridge; and,

FIG. 4 is a cross sectional view along 4-4 of FIG. 2 showing my new design of the nose portion of an ammunition cartridge.

1 Claim, 4 Drawing Sheets
